PULLING MACHINE

William E. O'Donnell, Wilmington, Del., and Robert W. Garey, Baltimore, Md.; Miriam L. Preston executrix of said William E. O'Donnell, deceased

Application April 8, 1948, Serial No. 19,708

2 Claims. (Cl. 29—259)

1

This invention relates to a pulling machine, which while capable of a wide variety of uses, is especially suitable for removing bars from stators or other like work pieces.

In traction motors it is a common practice to build a stator with field bars which are disposed transversely around the circumference of the stator and separated by mica or other suitable installation. The removal and replacement of such bars is a difficult and laborious operation. Even after heating the field laminations to soften the mica insulation it requires a considerable force, persistently applied, to extract a bar. With the use of tools which have heretofore been available for such work, it sometimes takes an hour of exhausting labor to remove a bar. The device of the present invention makes it possible for a single operator to remove such a field bar in about six minutes.

The principal object of our invention is to provide a power driven, portable, pulling machine capable of being easily brought to the work piece and of gripping and pulling the bars with a continuously applied force of appropriate magnitude, whereby such bars may be mechanically extracted in a short period of time.

A further object of the invention is to provide in such a machine means for adjusting the position of the bar extracting mechanism and for bracing the same against the work piece so that the pulling force may be most advantageously applied.

Other more specific objects and advantages of the invention, including those derived from simplicity of manufacture and ease of assembly of the parts of the machine, will become more fully apparent from the description, as hereinafter set forth, of one embodiment of the invention, having reference to the accompanying drawings, whereof:

Fig. 1 is a side elevation of a bar pulling machine of our invention, showing the same in the process of extracting an auxiliary bar from a stator, and with certain parts broken away and shown in section.

Fig. 2 is a plan view of the same.

Fig. 3 is a vertical end view of the machine as seen from the left of Fig. 1 with parts of the gear casing broken away to better disclose important features.

Fig. 4 is a transverse vertical section of the machine taken as indicated by the lines and arrows IV—IV in Fig. 1.

Fig. 5 is a longitudinal vertical section of the mechanism for driving the extracting means,

2 taken as indicated by the lines and arrows V—V in Fig. 2.

Fig. 6 is a transverse vertical sectional view of the gear casing, taken as indicated by the lines and arrows VI—VI in Figs. 1 and 5.

Fig. 7 is a vertical sectional view, taken as indicated by the lines and arrows VII—VII in Fig. 4, of the screw elevating mechanism for the pulling machine.

Fig. 8 is an enlarged fragmentary perspective view of the end of the extractor bar showing a gripper connected therewith and clamped to a main bar of the stator frame.

Fig. 9 is a similar fragmentary perspective view of the end of the extractor bar showing a gripper connected therewith and clamped to an auxiliary bar of the stator frame; and

Fig. 10 is an enlarged perspective view of the auxiliary bar gripper.

With particular reference to Figs. 1 and 2 of the drawings it will be seen that the pulling machine A of our invention is illustrated in association with the stator frame B of a traction motor. Such frame B is of a well known design, the commutator end being designated at 51, the commutator end being designated at 52, and the field being generally designated at 53. An auxiliary field bar 54 is shown in the process of being extracted.

As more clearly shown in Fig. 3, the stator frame selected for illustration has therein a series of auxiliary field bars 54 and main bars 55 disposed transversely around its circumference. It may be assumed that in the portion of the stator frame B shown at the right hand of the pulling machine in Fig. 3 the bars have been removed, whereas, in the portion shown at the left hand of the machine the field bars 54 and 55 are still embedded in the frame.

Of course, it will be appreciated that the stator frame illustrated herein represents only one example of a work piece to which the pulling machine of this invention may be advantageously applied, and in using the term "work piece" in the claims of this application, it is intended to include any motor frame or device which presents a similar problem as to the removal of bars or other elements which are frictionally held therein.

The pulling machine A consists generally of a portable frame having two sections: a ground engaging section including wheels 7, a handle portion 8, whereby the machine may be readily transported to the work, and an upright pedestal 9, forming the principal support for the extracting mechanism; and an elevatable section which

may be raised and lowered by a threaded rod 11 within the pedestal 9. Although the ground engaging section of the pulling machine frame may be variously designed, it is preferred to employ tubular standards 12 which merge together at their upper ends to form the handle portion 8, and tubular cross bars 13 which are welded to the standards 12 and to the pedestal 9. Conveniently the pulling machine frame may have incorporated therein cylindrical receptacles, such as shown at 14, and 15, and a box 16, all for accommodating tools, spare parts and accessories.

As shown most clearly in Figs. 1 and 4, the elevating screw 11 is operated by means of a hand crank 17 pivotally connected to a stub shaft 18 which is journaled in a bracket 19 and carries a bevel gear 21. As shown in Fig. 7, bevel gear 22 surrounds the elevating screw 11 and is internally threaded at 23 whereby its rotation serves to raise or lower the screw within the pedestal 9. Between the bevel gear 22 and the bracket 19, which is integrally attached to the pedestal 9, a thrust bearing 24 is interposed. In an obvious manner the turning of hand crank 17, depending upon the direction of its rotation, serves to raise or lower the elevatable section of the pulling machine.

At its upper end the elevating screw 11 joins a sleeve 25 within which a threaded extractor bar 26 is journaled. The sleeve 25 joins a gear casing 27 within which is mounted a worm wheel 28 having an internally threaded hub 29 meshing with the external threads of the extractor bar 26. As shown in Fig. 5, the worm wheel 28 is restrained against lateral movement within the gear casing 27. Hence its rotation serves to advance or retract the extractor bar 26 within the sleeve 25 of the pulling machine frame. An enlarged head 30 on the end of extractor bar 26 limits its advancing movement.

Worm wheel 28 meshes with a worm 31 on a shaft 32. As shown in Fig. 6, shaft 32 is mounted in bearings 33 within the gear casing 27, and one end of shaft 32 carries a spur gear 34 disposed within an adjoining, separate gear casing 35. Within gear casing 35 a pinion 37, mounted on the end of a shaft 38 and driven by a reversible electric motor 39, meshes with spur gear 34. Accordingly the motor 39 drives the worm wheel 28 through pinion 37 and worm 31.

Attached to the top of gear casing 27 is a housing 41 which carries a control mechanism for motor 39. Such mechanism is not shown in detail but includes a snap switch 42, which determines the direction of rotation of the motor 31, and a control handle 43 which may be turned to different positions, as represented by the numerals on the dial 44, to start, stop and regulate the speed of the motor 39.

At one end of sleeve 25 there is an annular groove 45 engaged by flanged clips 46 bolted to the cross head 47. The hub 48 of cross head 47 surrounds extractor bar 26 in such manner that it may turn freely thereon. By means of the flanged clips 46 it is at all times held in abutting relation to the end of sleeve 25 while it has capacity for relative rotation with respect to said sleeve. Furthermore the hub 48 of cross head 47 is internally provided with a key 49 which engages in a key-way 50 extending longitudinally through the threads of the extractor bar 26. In this manner the cross head 47, while restrained against relative rotation with respect to extractor bar 26, is free to slide longitudinally with respect to the extractor bar.

Cross head 47 has sleeves 51 at each end thereof, and such sleeves carry therein spacer bars 58, paralleling the extractor bar 26, one at each side thereof, and so designed that they are adapted to engage the stator frame B. In order to render adjustable the effective lengths of the spacer bars 58, each is provided with a series of regularly spaced perforations 59 with which locking pins 61 engage to form releasable locking connections between the cross head sleeves 51 and the spacer bars 58. To prevent the locking pins 61 from being removed from the machine they are desirably attached to the ends of chains 62, the other ends of the chains being secured to a ring 63 on the cross head 47. The cross head 47 with its spacer elements 58 serves to brace the portable frame of the pulling machine against the work while bars are being extracted from it. It will be seen that the reactive force exerted by the pull of the extractor bar is communicated to the sleeve 25 and thence to the hub 48 of cross head 47 and through spacer bars 58 to the stator frame.

At the reduced outer end of extractor bar 26 a connecting pin 64 couples the bar to a gripper which may take the form of a clamp as shown at 65 in Fig. 8. The clamp 65 has a yoke 66 at one end and a pair of screws 67 at the other end which penetrate into a cylindrical bore 68 within which the correspondingly shaped end of a main field bar 55 is adapted to fit.

When it is desired to remove an auxiliary field bar 54 the type of gripper shown at 65a in Figs. 9 and 10 is used. This gripper includes a yoke 66a connected to extractor bar 26 by pin 64 and has a bifurcated body 68a terminating in a reduced head 69a having a rectangular aperture 71a. To grip the end of an auxiliary field bar 54 the laminated sections 72a of the bar are passed through the aperture 71a of gripper 65a and are then separated by driving a wedge 73a between such sections, in the manner illustrated in Fig. 9. Desirably the wedge 73a has sawtoothed serrations 74a so that it will not easily become dislodged. When driven in place it spreads the laminated sections 72a so that they are firmly held within the bifurcated body 68a of the gripper 65a.

The operation of the pulling machine will be fairly apparent from the above description of its constituent elements. When the machine is used in association with a stator frame, such frame may be conveniently mounted on a work bench, such as shown at 75 in Fig. 1. If it is a large stator frame it may be found desirable first to mount it in one position and later, when half of the bars 54, 55 are removed from half of its circumference, to rotate it through one hundred and eighty degrees, and then to proceed to remove the remainder of the bars. Generally it is desirable to heat the field bars by an acetylene torch or the like to soften mica insulation around the field bars before attempting to remove them.

When applying the pulling machine to a field bar 54, 55 the appropriate gripper 65a, 65 is first mounted on the end of the extractor bar 26. The pulling machine is then transported to the work by wheeling it to a position near the bench 75. Thereupon the spacer elements 58 are initially adjusted, and by means of hand crank 17 the elevatable section of the frame is raised to a height where the extractor bar 26 is in line with the first field bar to be removed. By means of the motor controls, the extractor bar 26 may be brought to a position where the field bar can be clamped within the gripper. After such coupling

connection has been made between the extractor bar and the bar to be removed from the stator frame, a final adjustment of the pulling machine and its cross head 47 brings the free ends of the spacer bars 58 into contact with the stator frame, with such ends spanning the field bar, equidistant therefrom, and bearing against the stator frame at points on a chord across an arc of the stator circumference, as illustrated in Fig. 3.

It will be observed that the cross head 47 may be swung freely to any appropriate angle to brace the machine properly against the stator frame, such angle being desirably perpendicular to the plane of the field bar upon which the machine is to work. When the machine is thus adjusted with spacer elements 58 in contact with the work the motor 39 is set in operation in the proper direction to cause the extractor bar 26 to be retracted carrying with it the field bar engaged by its gripper. The speed of the motor may be appropriately regulated according to the pulling force needed for extraction of the field bar. After removal of the first bar, the pulling machine is readjusted for application to a second bar, and the process is repeated until all bars have been removed.

Although we have described in detail one specific embodiment of a bar pulling machine of our invention, it will be apparent that numerous changes may be made in the form of the machine, including particularly the manner in which it may be transported from one position to another (the term "portable" being used herein in its broad sense), the selection of mechanism for driving the extractor bar, and for elevating and depressing the extractor bar. It will also be apparent that various reversals of parts, and substitutions of equivalent mechanisms may be made, and that certain features of the invention may at times be used without use of other features, all without departing from the spirit of the invention as defined in the annexed claims.

Having thus described our invention, we claim:

1. A pulling machine for withdrawing a plurality of annularly disposed elements from a work piece having an outstanding peripheral strip, comprising a frame, a sleeve on said frame, a threaded elongated extractor bar mounted for

sliding and rotary motion within said sleeve, threaded means engaged with said threaded elongated extractor bar for longitudinally advancing and retracting said extractor bar, an elongated housing fixed to one end of said sleeve for enclosing said threaded means and providing spaced shoulders to prevent longitudinal movement of said threaded means, a peripheral groove provided on the other end of said sleeve, a cross head carried at said other end of the sleeve, means fastened to said cross head and engaged with said groove to prevent relative longitudinal motion between said sleeve and said head but allow rotary relative motion, a bore through the cross head through which the extractor bar extends, interengaging means between the cross head and the extractor bar to prevent relative rotary motion but to allow longitudinal relative motion, and a plurality of brace arms on said rotatable cross head for bracing said frame relative to a selected portion of the peripheral strip of the work piece during the period of application of extractive force on said extractor bar.

2. The apparatus as in claim 1 wherein the threaded means comprises a gear having an internally threaded hub, and the means fastened to cross said cross head constitutes a clip fastened at one end to said cross head and having an inturned flange at the other end in engagement with said groove, and wherein said interengaging means constitutes an elongated keyway in said extractor bar and a key carried by said cross head.
